UNITED STATES PATENT OFFICE.

JACOB STRAUS, OF ST. LOUIS, MISSOURI.

SADDLE.

SPECIFICATION forming part of Letters Patent No. 233,816, dated October 26, 1880.

Application filed June 9, 1880. (Model.)

To all whom it may concern:

Be it known that I, JACOB STRAUS, of St. Louis, in the county of St. Louis, and in the State of Missouri, have invented certain new and useful Improvements in Saddles; and I do hereby declare that the following is a full, clear, and exact description thereof, reference being had to the accompanying drawings, making a part of this specification, in which—

10 Figure 1 is a perspective view of my improved saddle. Fig. 2 is a plan view of the lower side of the same. Fig. 3 is a central longitudinal section of said saddle, and Fig. 4 is a cross-section of the same.

15 Letters of like name and kind refer to like parts in each of the figures.

In the use of riding-saddles great difficulty has heretofore been experienced in securing such shape as would render a saddle easy and comfortable to the horse and rider, and it has been necessary that for each size of saddle there should be a variety of shapes, in order that differences in the form of the back of the horse and the size and build of its rider might 20 be accommodated. In cases where the desired conformation of saddle could not be procured the result of using an ill-fitting saddle has been to make both horse and rider uncomfortable, and frequently to chafe and render sore 25 the back of the former.

It consists, principally, in an improved riding-saddle the tree of which is composed wholly of leather struck up or formed and shaped, stiffened, and stuffed substantially as 30 and for the purpose hereinafter specified.

It consists, further, in combining, with a saddle-tree composed wholly of leather struck up or formed and shaped, stiffened, and stuffed substantially as set forth, flaps which are attached to and form part of the same, substantially as and for the purpose hereinafter shown.

In the annexed drawings, A represents the seat, B the head, C the cantle, D the gullet, and E the shank, of my saddle, which parts 45 have the usual form when completed, and are constructed wholly from leather.

The seat A is molded or vamped upon a correspondingly-shaped block, after which the head B and gullet D have their inner contiguous edges stitched together, and the upper

edge of said head is then stitched to the front end of said seat. The cantle C and shank E are in like manner stitched together and to the rear end of said seat, after which the flaps F and the pad-leather G are stitched to the side 55 edges of said seat, the gullet D, and shank E, and said pad-leather secured by means of two rows of stitches, *a*, to the central portion of said seat, sufficient fullness being left between such rows of stitches and the lower side edges 60 of said pad-leather to enable the necessary stuffing of hair, H, to be placed between said leather and seat.

At the time of sewing together the edges of the seat A, flaps F, and pad-leather G the upper ends of a sweat-flap, I, and girth-strap K are inserted between said pad-leather and seat, and are secured in place by means of the line of stitches employed for connecting together the other parts named.

In order that the union between the seat A, gullet D, shank E, and the flaps F may be made more secure, I place a rivet, L, through said parts at suitable points, as seen in Fig. 1. Loops M, for breast-strap, crupper, &c., are 75 secured to the gullet D, seat A, and shank E, at suitable points, by means of rivets *m*, passed through said parts, as shown.

For an open-tree saddle, the seat A and pad-leather G are removed between the rows of 80 stitches *a*, as seen in Fig. 2.

The saddle thus described is constructed wholly from leather, and is flexible in all directions, so as to enable it to readily adapt itself to the shape of the horse, by which means 85 perfect ease and comfort are secured to the animal and all liability of injury to its back is avoided. The flexibility described enables the saddle to be fitted upon different horses, whatever differences may exist in the breadth and 90 concavity of their backs—a result which would not be obtainable were any other construction of tree employed.

In order that the pads may be made to fit over lumps or tender spots upon the back of 95 the animal, the leather G is provided with perforations *g*, through which an awl or other like instrument may be passed, and the stuffing H moved sidewise until the desired shape has been given to such portion of the pad.

If desired, the fork, cantle, and bars may be stiffened by the addition of thick leather or other suitable material, and the seat may be rendered elastic by the use of rubber.

5 The saddle thus constructed is light, durable, and very strong, is adapted to any climate, is no more expensive than other forms of saddle, and as it adapts itself perfectly to the back of a horse it cannot be turned while 10 the girth is properly fastened.

Having thus fully set forth the nature and merits of my invention, what I claim as new is—

15 1. An improved riding-saddle the tree of which is composed wholly of leather struck up

or formed and shaped, stiffened, and stuffed substantially as and for the purpose specified.

2. In combination with a saddle-tree composed wholly of leather struck up or formed and shaped, stiffened, and stuffed substantially as set forth, flaps which are attached to and form parts of the same, substantially as and for the purpose shown. 20

In testimony that I claim the foregoing I have hereunto set my hand this 2d day of 25 June, 1880.

JACOB STRAUS.
